UNITED STATES PATENT OFFICE

VINCENT V. VEENSCHOTEN, OF ERIE, PENNSYLVANIA, ASSIGNOR TO NORTHERN EQUIPMENT COMPANY, OF ERIE, PENNSYLVANIA, A CORPORATION OF PENNSYLVANIA

METHOD OF AND APPARATUS FOR FEEDING WATER TO BOILERS

Application filed May 17, 1922. Serial No. 561,726.

This invention is designed to control the feeding of water to a boiler and is of particular utility in connection with boilers subjected to wide ranges of pressure. Controlling devices for feeding water to boilers have heretofore been made which operate with closeness and give satisfactory results, such for instance, as the controlling device shown in the R. W. Andrews Patent, #1,148,483 where the boiler pressures are comparatively constant or desired to be constant but where the boiler pressures vary widely as in automobile construction or similar environments the variation in temperature of the steam due to variations in pressure seriously interferes with the proper functioning of the device. In the present invention this difficulty is obviated by subjecting the comparatively static element of the controlling instrument to the action of steam so that as the steam pressure varies with a consequent variation in temperature this disturbing factor is compensated for by an action of the steam on this comparatively static element.

The invention further consists in controlling the feed of the feed water with an expansion element by bypassing the excess of feed water.

The invention further involves the features of construction and method which will be hereinafter more particularly set forth in the specification and claims.

The apparatus is illustrated in the accompanying drawings as follows:—

Fig. 1 shows a boiler.

Fig. 2 a section of the fitting connecting the static element and expansion element and including an elevation of the controlling valve, the section being on the line 2—2 in Fig. 3.

Fig. 3 a section on the line 3—3 in Fig. 2.

Fig. 4 a section on the line 4—4 in Fig. 3.

Fig. 5 a plan view of the apparatus.

1 marks the boiler, 2 a feed water pump, 45 and 3 a water supply. These are of ordinary construction.

An expansion tube 4 is rigidly connected to a fitting 5, the fitting being connected by a pipe 6 to the steam space of the boiler. This expansion tube is inclined and the water level

A—A is normally about midway of the expansion tube. The lower end of the expansion tube is connected with a fitting 7, this fitting being connected by a pipe 8 with the water space of the boiler.

The normally static element of the device is in the form of a tube 9 connected with the fitting 5. This tube is constantly subjected to the steam from the boiler. The opposite end of the tube 9 is connected with a fitting 10 and the fitting 10 is connected by a flexible pipe 11 with the fitting 7 to prevent the formation of a dead end in the pipe 9.

A controlling lever 12 is in the form of two plates or arms which straddle the expansion tube 4. The plates are connected by an end piece 12^a and are pivoted on pins 13 extending from the fitting 7. A stud 14 extends from the fitting 10 through the plate 12^a and a nut 15 is screwed on the stud 14 against the plate forming a fulcrum for the lever. A plate 16 connects the arms of the lever at the free end of the lever and a spring 17 extends from this plate to the fitting 5, thus holding the lever against any slack.

Feed water is delivered to the boiler from the pump through a pipe 18, a check valve 19 being provided in the usual manner. A pipe 20 leads from the pipe 18 to a controlling valve 21 and a pipe 22 leads from the controlling valve to the supply tank 3. The pipes 20 and 22 form a bypass, therefore, in the feed water system.

The controlling valve has a body 23 with a way 24 through it, a valve plug 25 controlling the passage through the body, the plug having a way 26 adapted to be brought into register with the way 24. A lever 27 is fixed on the plug 25 and this lever is connected by a link 28 with the plate 16 on the free end of the lever 12.

It will readily be seen that as the tube 4 expands or contracts this movement is conveyed through the lever 12 to the lever 27 and the bypass valve actuated. This construction permits of a wide movement of the free end of the lever with a very small movement of the expansion tube. The double arm construction of lever balances the stresses so that there is no distortion under action.

It will be observed that inasmuch as the comparatively static element 9 is subjected at all times to steam pressure there is an expansion and contraction of this pipe coincident with the expansion and contraction of the tube 4 varying with steam pressures and consequently steam temperatures. Where the static element is a constant bar it does not take care of these variations so that with wide variations the response to differences in levels of water in the expansion tube is not what it should be. With this construction differences in level in the expansion tube are responded to correctly regardless of the steam pressure.

The way 26 is of sufficient amplitude to gradually open and close the bypass. This bypass is normally open to some extent so that there is a constant feeding of water varying as the requirements vary. There is also in the construction a lag which is fully described in the Andrews patent referred to in that the water level shifts so that as there is a greater discharge of steam the pull on the boiler is relieved to some extent by a dropping of the water level. This is accomplished in the structure shown either by making the expansion tube with a coefficient of thermal expansion but preferably by adjusting the size of the valve opening to the ordinary boiler requirements so that the feed water will give a perceptible lag in the water supply to the boiler requirements to which the apparatus responds. On the other hand, with a constant demand the water level remains comparatively constant. It will be understood, however, that this device is particularly designed for boilers subjected to such wide variations in demand as to very materially change the steam pressure. This also is taken care of in utilizing the variations in the level of water to take care of momentary variations in steam discharge. It will be noted that the bypass is of such amplitude that while it can vary the opening with the way 24 it cannot be swung to such an extent as to tend to close the valve with an extreme movement. Consequently where there is a movement past what would normally open the valve there is no closing of the valve by over-travel.

The expansion tube 4 operates on the same principle as in the Andrews patent above referred to, that is to say, the water in the tube is at a materially lower temperature than the steam in said tube. Consequently with a lower water level in the tube the tube as a whole is expanded to a greater extent than where there is a higher water level in the tube because a greater portion of the tube is subject to the higher temperature of the steam. On the other hand with a higher level of water in the tube a greater portion of the tube is subject to the water temperature and consequently the tube as a whole is at a

lower temperature and in consequence contracts.

What I claim as new is:—

1. In an apparatus for feeding water to boilers, the combination of a boiler; an inclined expansion tube connected to the water and steam spaces of the boiler; a comparatively static element in the form of a tube fixedly connected at one end to the expansion tube and connected to the steam space of the boiler, said tubes having expansion coefficients and relative water and steam exposures to neutralize variations incident to variations in steam pressure; a feed water device; and means actuated by the relative movement of said tubes controlling the device. 70 75 80

2. In an apparatus for feeding water to boilers, the combination of a boiler; an inclined expansion tube connected to the water and steam spaces of the boiler, the tube crossing the water line of the boiler; a comparatively static element in the form of a tube operatively connected at one end to the expansion tube and connected to the steam space of the boiler, said tubes having expansion coefficients and relative water and steam exposures to neutralize variations incident to variations in steam pressure; a feed water device; and means actuated by the relative movement of said tubes controlling said device. 85 90 95

3. In an apparatus for feeding water to boilers, the combination of a boiler; an inclined expansion element in the form of a tube connected to the water and steam spaces of the boiler, the tube crossing the water line of the boiler; a comparatively static element operatively connected at one end to the expansion tube; means acting on said elements neutralizing variations incident to variations of steam pressure in the expansion tube; a feed water device; and means actuated by the relative movement of said elements controlling the device. 100 105 110

4. In an apparatus for feeding water to boilers, the combination of a boiler; an expansion element in the form of an inclined tube connected to the steam and water spaces of the boiler; a comparatively static element operatively connected to one end of the expansion element; a feed water device; and a lever controlling the feed water device formed of two arms, one at each side of the tube, said arms extending the major portion of the length of said tube and operatively connected at its free end to the feed water device and at its opposite end to the tube and element at points remote from the connection between the tube and element. 115 120 125

5. In an apparatus for feeding water to boilers, the combination of a boiler; an expansion element in the form of an inclined tube connected to the steam and water spaces of the boiler; a comparatively static element 130

operatively connected at one end to the expansion element; a feed water device; and a lever controlling the feed water device formed of two plates straddling the tube and 5 extending throughout the major portion of the tube, said lever being operatively connected at opposite sides of said tube and to said static element at points remote from the connection between said tube and said element.

10 6. In an apparatus for feeding water to boilers, the combination of a boiler; an expansion element in the form of an inclined tube connected to the steam and water spaces 15 of the boiler; a comparatively static element operatively connected at one end to the expansion element; a feed water device; a controlling lever formed of two plates straddling the tube and extending throughout the 20 major part of the length of the tube and connected to the tube; an end piece between the plates; an adjustable connection between the static element and the end piece, the connections between the lever and the tube and 25 between the end piece and the element being remote from the connection between the tube and element; a bridge piece between the plates at the opposite end of the lever from the end piece; and a connection between the 30 bridge piece and the feed water device.

7. The method of feeding water to boilers having as a means of control thermal elements, one of which is exposed to steam pressure and to a varying exposure of steam and 35 water with variations of water level and in which the expansion of said element due to variations in the water and steam is utilized through connection with the other element which is comparatively static in controlling 40 the water supply which consists in maintaining a substantially constant relation between said elements with variations of pressure through the application of steam by expanding both elements in response to variations 45 of steam pressure.

In testimony whereof I have hereunto set my hand.

VINCENT V. VEENSCHOTEN.
